(57) **CLAIM**

The ornamental design for a LED trouble light with clamp,
as shown and described.

DESCRIPTION

FIG. 1 is a front bottom left side perspective view for a LED trouble light with clamp, showing our new design with hook folded in the back and clamp in non-rotated position;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top perspective view of FIG. 1 thereof;

FIG. 7 is a bottom perspective view of FIG. 1 thereof;

FIG. 8 is a front bottom left side perspective view of FIG. 1 thereof, with hook in extended position and clamp in non-rotated position; and,

FIG. 9 is a front bottom left side perspective view of FIG. 1 thereof, with hook folded in the back and clamp rotated to the front position.

The broken lines indicate portions of the design that form no part of the claimed design.

1 Claim, 9 Drawing Sheets
